(57) **CLAIM**

The ornamental design for a personal care kit, as shown and described.

DESCRIPTION

FIG. 1 is an exploded front perspective view of the personal care kit according to our new design;

FIG. 2 is a bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines are included for the purpose of illustrating the unclaimed portions of the personal care kit and form no part of the claim.

1 Claim, 8 Drawing Sheets
